UNITED STATES PATENT OFFICE.

R. HARRY STONE, OF IRVINGTON, NEW JERSEY, ASSIGNOR TO TITEFLEX METAL HOSE CO., A CORPORATION OF NEW JERSEY.

DIE-CUTTING APPARATUS.

Application filed February 19, 1927. Serial No. 169,449.

My invention relates to apparatus for forming dies and has for an object to provide a machine of simple construction in which dies may be readily made to uniform standards of form and dimension.

A specific object of my invention is to provide a machine for forming certain dies used in making metal hose of the type comprising a spirally wound metal ribbon. In such hose the edges of the ribbon are formed to interlock by passing them through dies, and the wear on the dies in service is so severe that the dies must be frequently replaced with new ones. The form of the dies is peculiar and somewhat intricate, and heretofore they have had to be made by hand at considerable expense, owing to the precision in form and dimension requisite. Hence the replacement of dies in such metal hose manufacture has involved a high maintenance item.

It is an object of my invention to provide a semi-automatic die-cutting machine which will reduce the time and cost of making new dies for metal hose manufacture and which will insure uniformity in the dies and a strict adherence to standards of form and dimension.

Another object of my invention is to provide a machine which will form a die in a minimum number of operations.

While a specific object of my invention is to provide a machine for making dies used in metal hose manufacture, it will be evident that my invention could also be used in forming other products, and hence, I do not limit my invention to the specific application above referred to.

With the above named objects in view, and other objects which will appear hereinafter, I shall now describe an embodiment of my invention and define the novelty and scope of my invention in the claims.

In the accompanying drawings,

Figure 1 is a side view of my improved die-cutting machine;

Fig. 2 is a plan view of the machine with certain parts broken away;

Fig. 3 is a side view, partly in section, of a fragment of my machine showing the manner of mounting a die-blank in the machine;

Fig. 4 is an end view, partly broken away, of the parts shown in Fig. 3;

Figs. 5 and 6 are end views of a die after the first and final operations, respectively, have been performed thereon by the machine;

Figs. 7 and 8 are side views of the die shown in Figs. 5 and 6 respectively, as viewed in the direction of the arrows 7 and 8 respectively, and

Figs. 9 and 10 are side views of the die shown in Figs. 5 and 6 respectively, as viewed in the direction of the arrows 9 and 10 respectively.

As shown in Figs. 1 and 2 my improved die-cutting machine is provided with a base 15 formed near opposite ends thereof with ways 16 and 17 respectively. These ways are adapted to support carriages 18 and 19 respectively. Between the ways are a pair of brackets 20 bolted to the base and adapted to provide bearings for a spindle 21. Mounted on the spindle between the brackets 20 is a driving pulley 22 which has spline connection with the spindle so as to permit the spindle to slide axially in its bearings. At the right-hand end of the spindle, as viewed in the drawings, I provide a face plate 23 which is preferably screwed upon the spindle, as shown in Fig. 3. Secured to the opposite end of the spindle is a cam plate 24. A compression coil spring 25 is fitted about the spindle 21 between the cam plate 24 and the adjacent bracket 20. This spring serves normally to press the spindle endwise toward the left, as shown in drawings. A stop screw 26 which passes through a threaded bore in a bracket 27 secured to the left-hand end of the machine, serves to hold the cam from engagement with the tracing finger 46 under the influence of the spring 25 during periods of adjustment or at any desired times. The stop screw is provided with a handle 28 by which the screw may be adjusted in the bracket 27.

A feed screw 29 mounted in suitable bearings 30 and 31 at the front and rear respectively, of the machine serves to feed the carriage 18 transversely across the base 15. The feed screw 29 carries a handle 32 at the forward end, and mounted on the feed screw adjacent the handle, is a graduated collar 33 which provides means for determining the angular movement of the feed screw. Mounted on the carriage 18 is a slide rest 34 upon which is supported a tool post 35 adapted to hold a tool 36. The slide rest 34 is similar to that of a lathe and is provided with means for moving the tool post toward and from the spindle, as well as transversely with respect to the spindle, the transverse movement being

controlled by a handle 37 and the longitudinal movement parallel to the spindle by a handle 38.

Mounted at the opposite end of the machine is a feed screw 39 which extends transversely across the base 15 and is supported in suitable bearings 40 and 41 at the front and rear respectively, of the machine. This feed screw serves to feed the carriage 19 transversely across the machine. Like the feed screw 29 the feed screw 39 is provided with a handle 42 and with a graduated collar 43. Rising from the face of the carriage 19 is a post 44 which supports a collar 45 provided with a lug or tracing finger 46.

The feed screws 29 and 39 are adapted to turn in mutually timed relation. To this end the feed screw 29 at its rear end carries a bevel gear 47 which engages a pinion 48 mounted on a shaft 49. The latter has bearings in brackets 50 and 51 secured to the rear of the base 15. The shaft 49 at the left-hand end thereof carries bevel gear 52 which meshes with a bevel pinion 53 secured upon the rear end of the feed screw 39. Thus when the screw 29 turns, the screw 39 is also turned, but at a higher speed, due to the step-up gearing connecting the feed screws. Hence for any given transverse movement of the carriage 18 there is a corresponding but multiplied movement in transverse direction of the carriage 19. It will also be observed that the feed screws 29 and 39 turn in opposite directions and because both of the screws have right-hand threads, one carriage will travel forward while the other carriage is traveling toward the rear.

The form of the dies which this machine is especially adapted to cut, is shown in Figs. 6, 8 and 10. It is to be understood, however, that while the apparatus is so especially adapted it may be used to cut other and different forms of dies. The manner of forming the particular form of die shown in the drawing will now be described as illustrative. The die-blank is a hollow cylindrical member which is cut away at one side by a slot 55. This slot extends from the cutting face of the die to a point near the base or opposite face of the die. One wall 56 of the slot 55 lies in a plane radial to the axis of the cylinder, while the opposite wall 57 lies approximately at right angles to the wall 56. The finished die is formed with a stepped spiral cutting face comprising two narrow co-axial spiral ledges. The inner ledge 58 projects beyond the outer ledge 59 and is bounded on the inside by the inner peripheral wall of the hollow die-blank and on the outside by a cylindrical wall 60. The pitch of the ledges is right-handed, in other words, it advances from the wall 56 to the wall 57. The outer spiral ledge 59 however has a sharper pitch than the inner spiral ledge 58 and a conoidal tapered wall 60' serves to connect wall 60

and the ledge 59. Adjacent the wall 56 the pitch of the ledges changes to a steeper grade, as indicated at 61 and 62 respectively.

The manner of securing a die-blank upon the face-plate 23 is illustrated in Fig. 3. The face-plate is formed with a recess 63 in which is fitted a clutch plate 64. The latter is provided with a central bore 65 into which projects a radial pin 66. The bore 65 is of a size to snugly engage the body of a die-blank. A die-blank is inserted into the bore 65 from the rear of the plate with the pin 66 entering the slot 65 and engaging the wall 56. In this position the die-blank may be held by a set screw 67, which is threaded radially through the plate 64. The plate 64 is narrower than the length of the die-blank so that the latter projects from the front face of the plate far enough to permit of cutting the spiral face of the die. After the die-blank has been inserted in the plate 64, the latter is seated in the recess 63 and secured to the face-plate 23 by means of bolts 68. These bolts draw the blank into the recess 63 which serves to center the die accurately with respect to the spindle 21.

In operation the die-blank is first cut to form the inner spiral ledge 58 which, as explained before, stands out in relief from the rest of the cutting face, and is bounded by a vertical wall 60 at the outer periphery thereof. The cam plate 24 is accordingly formed with two concentric face cams 70 and 71 respectively, the outer cam 71 being used to control the first cutting operation in which the inner spiral ledge 58 is formed, while the inner cam surface 70 is used in the second cutting operation to control the cutting of the surfaces 59 and 60'. For the first operation therefore the tracer finger 46 must be moved into contact with the outer cam surface 71, which is done turning the feed screw 39 to move the finger 46 into contact with the outer cam 71. In the meantime it is necessary to move the spindle 21 toward the right so that the finger 46 will clear the surface of the cam while it is being adjusted to initial position. Such axial movement of the spindle is effected by screwing the set screw 26 against the cam until it has been moved sufficiently to clear the tracer finger. After the finger has been properly positioned the set screw is turned back, releasing the cam so that it will be forced by the spring 25 against the finger 46.

The face of the annular cam 71 is in the form of a spiral which parallels the face of the ledge 58 which is to be cut in the end of the die. In other words, the spiral of the cam although much larger than that of the die has the same axial advance per unit of angular displacement as the spiral of the ledge 58 and includes a change of pitch through a certain portion of the cam surface to firm the steeper part 61 of the ledge.

The pulley 22 turns in the direction of the arrow shown in Fig. 2, and as the die-blank is rotated by the pulley, it is advanced toward the tool 36 by engagement of the cam 71 with the tracer finger 46, and, consequently, the tool makes a spiral cut in the end of the die-blank which extends from the wall 57 to the wall 56 and parallels the cam surface. The cam 70 is also provided with a reversely spiralled surface which permits the die-blank to return axially to its original position under pressure of spring 25, while the slotted part of the die-blank is passing the tool. By this means the entire end surface of the blank is faced off on a spiral coinciding with the faces 58 and 60. It will be understood, of course, that a number of cuts are required to face off the end of the die and in making this cut the carriages 18 and 19 preferably remain stationary while the tool 36 is fed transversely by operating the handle 37 and axially by operating the handle 38.

After the entire face of the blank has been properly faced off, the outer portion of the surface is cut down to a greater depth, as shown at 69, so as to leave the ledge 58 standing out in relief and bounded on the outer edge by the cylindrical wall 60. This completes the first operation on the die-blank which is controlled as to pitch by the cam 71 and the die then presents the form shown in Figs. 5, 7 and 9.

In the second operation the outer ledge 59 and conoidal wall 60' are formed under control of the inner cam 70. The stop screw 26 is first adjusted to move the cam plate 24 axially to the right, so that the finger 46 may be adjusted to proper position with respect to the cam 71, after which the stop screw is retracted to permit the cam 70 to engage the tracer finger. Also the tool 36 is adjusted to the work either by adjusting the tool in the post or the feeds controlled by the handles 37 and 38 or all of them. The cam 70 reacting against the finger 46 feeds the die toward the tool 36 at such a rate with respect to its angular movement as to cut the ledge 59 with its sharply inclined portion 62 in the outer part of the face 69. The cam 70 is also so formed as to cause the conoidal face 60' to be cut in the die-blank, connecting the ledges 59 to the base of the wall 60. Owing to the varying taper or inclination of the conoidal wall 60', the die-blank must be shifted axially in proper proportion to the transverse feed of the tool 36. For this reason the carriage 18 is geared to travel in timed relation to the travel of the carriage 19, so that as the finger 46 traverses the cam 70 and moves the die-blank toward the tool the latter will have a proportionate transverse movement. In order to provide for extreme accuracy in cutting the dies the cam 70 is made many times larger in diameter than the die, and hence the speed of the tracer carriage 19 is proportionately

greater than the speed of the tool carriage 18. In the second operation transverse feed is controlled not by the handle 37 but by the feed screw 29 which may be operated either by the hand-wheel 32 or by the hand-wheel 42, the latter permitting of a very fine transverse feed of the tool. It may be noted that the surface of the cam 70 is reversed with respect to the surface to be cut in the die-blank because the finger 46 travels radially outward while the tool 36 travels radially inward toward the axis of the spindle. As in the case of cam 71, the cam 70 is provided with a reversely spiralled surface which operates to return the die-blank to its original longitudinal position, while the slotted portion thereof is passing the tool 36.

I have described in considerable detail a specific form of die-blank and the manner in which it is cut on the machine, but it is very evident that other forms may be cut in a piece of work carried by the spindle without involving any change in my machine, other than that of replacing the cams 70 and 71 with different cams. It will also be understood that various changes could be made in the form and structure of my improved machine without departing from the spirit and scope of my invention as defined in the following claims.

I claim:

1. In a machine of the character described, a spindle mounted to rotate and to reciprocate axially, a chuck mounted on one end of the spindle, a cam mounted on the other end of the spindle, a tracer, a spring adapted to press the cam against the tracer whereby the cam and tracer will co-act to reciprocate the spindle during rotation thereof, means operating to feed the tracer radially across the face of the cam during rotation of the spindle, a tool adapted to be held in cutting engagement with a piece of work held in the chuck and a mechanism for moving the operating means and tools.

2. In a machine of the character described, a spindle mounted to rotate and to reciprocate axially, a chuck mounted on one end of the spindle, a cam mounted on the other end of the spindle, a tracer, a spring adapted to press the cam against the tracer whereby the cam and tracer will co-act to reciprocate the spindle during rotation thereof, means operating to feed the tracer radially across the face of the cam during rotation of the spindle, a tool adapted to cut a piece of work held in the chuck, and a means for feeding the tool transversely across the face of the work cooperating with the operating means.

3. In a machine of the character described, a spindle mounted to rotate and to reciprocate axially, a chuck mounted on one end of the spindle, a cam mounted on the other end of the spindle, a tracer, a spring adapted to press the cam against the tracer whereby the cam

and tracer will co-act to reciprocate the spindle during rotation thereof, means for feeding the tracer radially across the face of the cam during rotation of the spindle, a tool adapted to cut a piece of work held in the chuck, and means for feeding the tool transversely across the face of the work, in timed relation to the movement of the tracer across the face of the cam.

10 4. In a machine of the character described, a spindle mounted to rotate and to reciprocate axially, a chuck mounted on one end of the spindle, a cam mounted on the other end of the spindle, a tracer, a spring adapted to press the cam against the tracer whereby the cam and tracer will co-act to reciprocate the spindle during rotation thereof, means for feeding the tracer radially across the face of the cam during rotation of the spindle, a tool adapted to cut a piece of work held in the chuck, means for feeding the tool transversely to the axis of the spindle in timed relation to the movement of the tracer across the face of the cam, and independent means for feeding the tool transversely to the spindle.

5. In a machine of the character described, a spindle mounted to rotate and to reciprocate axially, a chuck mounted on one end of the spindle, a cam mounted on the other end of the spindle, a tracer, a spring adapted to press the cam against the tracer whereby the spindle will be reciprocated during rotation thereof, means for feeding the tracer radially across the face of the cam, a tool adapted to cut a piece of work held in the chuck, means for feeding the tool transversely to the spindle in timed relation to the movement of the tracer across the face of the cam, independent means for feeding the tool transversely to the spindle, and means for feeding the tool in a direction parallel to the axis of the spindle.

6. In a machine of the character described, a spindle mounted to rotate and to reciprocate axially, a chuck mounted on one end of the spindle, a cam mounted on the other end of the spindle, a tracer, a spring adapted to press the cam against the tracer whereby the spindle will be reciprocated during rotation thereof, means for feeding the tracer radially across the face of the cam, a tool adapted to cut the face of a piece of work held in the chuck, and means for feeding the tool transversely to the spindle, the cam having a larger diameter than the face of the work and the feed of the tracer being proportionately greater than the feed of the tool.

7. In a machine of the character described, a spindle mounted to rotate and to reciprocate axially, a chuck mounted on one end of the spindle and adapted to hold a piece of work, a cam plate mounted on the other end of the spindle, said plate being formed with a pair of concentric cam surfaces on the face thereof, the radius of the inner cam surface being greater than the radius of the face of the

work, a tracer, a spring adapted to press the cam surfaces against the tracer whereby the spindle will be reciprocated during rotation thereof, means for feeding the tracer radially across the cam surfaces, a tool adapted to be moved into cutting engagement with the work, means for feeding the tool across the face of the work in timed ratio to the movement of the tracer across the face of the cam, said ratio being equal to the ratio of said inner cam face with respect to the face of the work.

8. In a machine of the character described, a spindle mounted to rotate and to reciprocate axially, a chuck mounted on one end of the spindle and adapted to hold a piece of work, a cam plate mounted on the other end of the spindle, said plate being formed with a pair of concentric cam surfaces on the face thereof, a tracer, a spring adapted to press the cam face of the plate against the tracer whereby the spindle will be reciprocated during rotation thereof, means for feeding the tracer transversely to the spindle, a tool adapted to cut the face of a piece of work held in the chuck, and means for feeding the tool transversely of the spindle, the radius of one of the cam surfaces being greater than the radius of the face of the work, and the feed of the tracer being proportionately greater than the feed of the tool.

9. In a machine of the character described, a spindle mounted to rotate and to slide axially, a chuck at one end of the spindle adapted to hold a piece of work, a cam at the other end of the spindle, a tracer, a cutting tool adapted to be held in cutting engagement with the work, said cam and finger co-acting to reciprocate the spindle during cutting of the work, and means in the chuck for positioning the work angularly with respect to the cam.

10. In a machine of the character described, a spindle mounted to rotate and to slide axially, a chuck at one end of the spindle adapted to hold a piece of work, a cam at the other end of the spindle, a tracer, a cutting tool adapted to be held in cutting engagement with the work, said cam and finger co-acting to reciprocate the spindle during cutting of the work, the work being formed with a slot, and a pin in the chuck adapted to engage a wall of the slot to fix the angular position of the work with respect to the cam.

11. In a machine of the character described, a spindle mounted to rotate and to slide axially, a chuck at one end of the spindle adapted to hold a piece of work, a cam at the other end of the spindle, a tracer, a cutting tool adapted to be held in cutting engagement with the work, said cam and finger co-acting to reciprocate the spindle during cutting of the work, the work being formed with a slot, and a pin in the chuck adapted to engage a wall of the slot to fix the angular position of the work with respect to the cam, and a set

screw in the chuck for holding the work in said angular position.

12. In a machine of the character described, a base, a tracer carriage movable across the base at one end thereof, a tool carriage movable across the base at the other end thereof, feed screws adapted respectively to move the tracer carriage and the tool carriage, a train of gears connecting the feed screws, a spindle mounted to rotate between the carriages on an axis transverse to the movement of the carriages, said spindle being also movable axially, a chuck mounted on the spindle adjacent the tool carriage, a face cam mounted on the spindle adjacent the tracer carriage, a tracer finger carried by the tracer carriage and adapted to engage the cam to move the spindle axially during rotation thereof, a spring acting to hold the cam in engagement with the tracer finger, and a tool carried by the tool carriage and adapted to cut the work held in the chuck.

13. In a machine of the character described, a base, a tracer carriage movable across the base at one end thereof, a tool carriage movable across the base at the other end thereof, feed screws adapted respectively to move the tracer carriage and the tool carriage, a train of gears connecting the feed screws, a spindle mounted to rotate between the carriages on an axis transverse to the movement of the carriages, said spindle being also movable axially, a chuck mounted on said spindle adjacent the tool carriage, a face cam mounted on the spindle adjacent the tracer carriage, a tracer

finger carried by the tracer carriage, and adapted to engage the cam to move the spindle axially during rotation thereof, a spring acting to hold the cam in engagement with the tracer finger, a slide rest carried by the tool carriage, and a tool carried by the slide rest.

14. In a machine of the character described, a base, a tracer carriage movable across the base at one end thereof, a tool carriage movable across the base at the other end thereof, feed screws adapted respectively to move the tracer carriage and the tool carriage, a train of gears connecting the feed screws, a spindle mounted to rotate between the carriages on an axis transverse to the movement of the carriages, said spindle being also movable axially, a chuck mounted on the spindle adjacent the tool carriage, a face cam mounted on the spindle adjacent the tracer carriage, a tracer finger carried by the tracer carriage and adapted to engage the cam to move the spindle axially during rotation thereof, a spring acting to hold the cam in engagement with the tracer finger, a slide rest carried by the tool carriage, and a tool carried by the slide rest, the tool being adapted to cut the face of a piece of work held in the chuck, the cam being of larger diameter than the face of the work and the movement of the tracer carriage being proportionately greater than the movement of the tool carriage.

In testimony whereof I have signed this specification this 19th day of January, 1927.

R. HARRY STONE.
